UNITED STATES PATENT OFFICE.

JULIUS R. WEMLINGER, OF BROOKLYN, NEW YORK.

BULKHEAD CONSTRUCTION.

1,137,938.

Specification of Letters Patent.

Patented May 4, 1915.

Application filed November 23, 1912. Serial No. 733,205.

To all whom it may concern:

Be it known that I, JULIUS R. WEMLINGER, a citizen of the United States, residing in the city of Brooklyn, in the county 5 of Kings and State of New York, have invented certain new and useful Improvements in Bulkhead Construction; and I do hereby declare the following to be a full, clear, and exact description of the invention, such as will enable others skilled in the art to which it appertains to make and use 10 the same.

My invention relates to improved constructions adapted for use as bulk-heads, 15 dock-walls, wharves, sea-walls, canal or other embankments, retaining-walls, etc., and in fact for any purpose or location where earth or other materials have to be retained with vertical or inclined faces.

20 As illustrated herein my invention comprises the use of metallic sheet piling, which may be of any form of construction. The sheet piling is driven into and through the ground to a sufficient depth below the surface 25 of the materials on the outer or deeper side thereof, and after this is done the upper portion thereof is provided with a concrete facing and coping to form a neat and substantial finish, well adapted to withstand the service, weather and other conditions imposed thereon.

The metal piling used in my construction may be driven in any of the various manners customary for this purpose and the 35 depth or length of the piling should be such as to penetrate a sufficient distance into solid or stable earth, etc., so as to securely anchor said piling at its bottom portion to enable it to resist the thrusts of the materials inclosed 40 thereby. The upper portion of the said piling may also be anchored to the inclosed material, taking care that the anchor bolts for this purpose extend well beyond the natural slope which such material will assume when in its free condition whether wet 45 or dry. In other words, both the top and bottom anchorage should be made secure to best serve the intended purposes.

In cases where my improved bulk-head 50 construction is used for walls adjoining water or water courses, such as ship channels, canals, wharves, docks, etc., the piling

may be driven until the lower portion is embedded in a substantial stratum, preferably impervious to water, if such be found, such 55 as clay, hard-pan, etc., and after the piling is thus placed and anchored, the earthy or other material may be excavated from the outer side by dredging or otherwise to the depth required. This method of construction, therefore, provides a temporary means for preventing slides of earth into a canal or other water course, or into an earth cut, while the dredging or excavating of the same is being accomplished, and when finished, 60 my bulk-head forms a permanent retaining wall, establishing a stable support for the earth or other material. This, therefore, minimizes the labor and expense and obviates the necessity of excavating or grading 65 the banks to their slope of repose.

If the level of the top of my finished bulk-head is to be higher than that of the natural surface adjoining the same, the dredged or excavated material from the 70 outer side thereof may be deposited on the inner side, thereby further minimizing the expense and labor of construction. If material impervious to water, such as clay, etc., 75 is easily available, that portion of the back-filling adjoining the sheet piling may be formed thereof and this will thereby serve to further protect and reinforce the structure. Where water is apt to collect behind the structure, weep holes or drains may be 80 provided to allow it to escape and thereby lessen the pressure on the wall.

My construction is particularly adapted for use along streams, canals or waterways which are to be subsequently deepened, or 85 along streets, railroad cuts, etc., and if desired, my bulk-head may be completed before any of the excavating is done. In this case, the sheet piling would be driven from, or above, the existing surface of the ground, 90 and after a part or the whole of the sheet piling is driven and anchored, dredging or excavating may be done and the excavated material may be used as back-filling to form 95 part of the finished back.

Having thus given a general description 100 of my invention, I will now, in order to make the matter more clear, refer to the one sheet of drawings which forms part of this

specification and in which like numbers refer to like parts:—

Figure 1 is a transverse vertical cross section of a bulk-head of my construction in connection with a wharf, dock, or canal. Fig. 2 is an isometric view of a part of the upper portion of one form of my construction showing, in this case, corrugated metallic sheet piling with concrete on the front and rear faces of the upper portion thereof. Fig. 3 is a transverse section of a modified form of construction of the upper part of a bulk-head wall, the details of which are slightly different, but within the scope of my invention.

Referring now to the various numbers of reference on the drawings:—1 indicates metallic sheet piling, the form shown in Fig. 2 being made of corrugated plates with locking strips 2, secured thereto; and although this style lends itself readily to the purpose intended, I wish it understood that other forms of metallic sheet piling may be used in this connection.

As shown in Fig. 1, 3 indicates a metal channel secured horizontally to the outside surface of the sheet piling and adapted to retain and assist in the support of the concrete facing thereon.

As shown in Fig. 2, 4 indicates the outer upwardly extending flange of a thin metal plate, the horizontal portion of which, as indicated at 5, is cut into scallops or corrugations as shown, to fit within the grooves of the corrugated piling as illustrated, thereby forming a tight support for the concrete which is deposited thereon after mixing. The scalloped plate is supported against the outer face of the piling by Z-shaped clips 6 attached to the piling and on which the flanged and scalloped plate rests as shown.

Temporary forms may be used in the customary manner for holding the concrete in position while being placed and during its period of setting, after which, the temporary forms may be removed as customary.

As shown in Fig. 3, 7 indicates a Z-bar member extending horizontally along the outer face of the metallic piling adapted to hold and strengthen the lower edge of the concrete facing. In the several views, short pieces of Z-bar or bracket sections 8 are attached to the outer face of the sheet piling to serve as anchors for the concrete for the purpose of holding the same firmly in position.

As shown in Fig. 1, 9 is an anchor bolt passing through the metallic piling near the upper part thereof, which bolt extends backwardly into the earth or other material for a distance sufficient to insure proper anchorage by attachment to the anchor plate or bar 10. This anchor plate 10 is preferably

located at such a distance back from the face 65 of the bulk-head that it is beyond the angle of repose of the filling material whether the same be wet or dry. In other words, the anchor extends into the stable material in order to accomplish its purpose. This 70 anchor plate may be embedded by excavation and back filling, or it may be driven as a pile into firm earth as desired.

As shown in Fig. 3, 11 is an anchor bolt provided with a washer 12, for uniting the 75 upper portion of the metallic sheet piling to the concrete coping.

As indicated in the various views 13 is a front facing formed of concrete deposited 80 in place against the sheet piling and anchored thereto by the anchors 8 previously mentioned; and in the preferred form the facing 13 is provided with an upper and rearwardly extending portion or coping 14, which provides a substantial finish for my 85 construction, as shown in Figs. 1 and 2.

The front facing of concrete may be provided with further reinforcement consisting of metallic fabric 15 embedded therein, and as shown in Fig. 1, this extends backwardly over the tops of the piling into the coping 14. In case a rear facing of concrete is used, as indicated in Figs. 2 and 3, this may be provided with a similar metallic fabric reinforcement indicated as 16. These 95 reinforcements 15 and 16 may be composed of rods, wires, expanded metal, wire mesh fabric, or other suitable materials for this purpose. The reinforcement 15 may be secured to the anchors 8.

As shown in Figs. 1 and 3;—17 indicates the filling or embankment in the rear of my bulk-head and supported thereby, which may be composed of any suitable substances such as earth, sand, broken stone, or in fact 105 any available materials. In case, however, that clay or similar material, which is impervious to water, is available from the excavation or otherwise, I prefer to place a layer of the same immediately adjoining the rear 110 portions of the metallic sheet piling to protect it.

As indicated in Figs. 1 and 3, 18 represents the water in a harbor, dock, canal, etc., below which is indicated the silt or other 115 material composing the bottom 19; while the lowest material indicated as 20 in Fig. 1 is solid earth, clay, hard-pan or other substantial formation, such as will be adapted to form a firm support for the lower end of 120 the piling and enable it to resist the lateral, vertical or other pressures to which it will be subjected in use.

As shown in Fig. 1, 21 represents a string 125 piece or fender timber secured to the upper part of the bulk-head by the bolts 22, as shown, or it may be secured at a distance of a few inches from the facing by using spac-

ing blocks, thereby providing more elasticity, if desired. This serves to protect the bulk-head from impact and also protects vessels or barges which come in contact therewith. 5 24 represents the concrete backing in case where this is used.

As shown in the drawings the concrete facing extends to a certain distance below the water surface and preferably to a sufficient depth below the low-water level, so that the metallic piling will at no time be exposed to the destructive action of the air which would cause corrosion, and at the same time the concrete facing protects the material at, near and above the water surface. If desired to more fully protect the metal piling, the facing 13 may extend to, or into, the bottom 19, or to the lower material 20. When used as a retaining wall the 20 concrete may extend a short distance below the earth surface on the outside of the wall.

Instead of using metal fabric reinforcement as shown, I may lay rods 23 in the re-entrant angles of the anchor clips 8 as illus- 25 trated in Fig. 3, and these rods may be fur- ther supported or connected vertically, if de- sired, by other rods secured thereto by tie wires or otherwise.

From the foregoing, it will be seen that 30 my construction has the advantage of avoiding duplication of work and material, for the reason that the sheet piling which forms part of the permanent structure is also used to support the bank of earth during the con- 35 structive period, and the finished structure has a solidity, strength and permanence es- sential to long life.

Although for the sake of simplicity of de- 40 scription and phraseology in the claims I have quite generally referred to the subject matter of my invention as a bulk-head con- struction, I wish it understood that this is adapted for use as bulk-heads, dock walls, 45 sea walls, canal or other embankments re- taining walls, and in fact for any purpose or location where earth or other materials have to be retained in position with vertical or sloping faces.

Although I have shown and described my 50 improvements in considerable detail, I do not wish to be limited to the exact and specific details shown and described, but may use such substitutions, modifications or equivalents thereof, as are embraced within 55 the scope of my invention, or as pointed out in the claims.

Having thus described my invention, what I claim and desire to secure by Letters Patent is:—

60 1. A bulk-head construction comprising a wall of metallic sheet piling the lower portion of which is driven into earth adapted to hold the same, a plurality of anchors connected to said wall and extending into the

bank in the rear thereof, thereby securing 65 the upper portion of the said wall, a bracket support secured horizontally to the outer surface of the said piling at an intermediate portion thereof, a concrete facing applied to the upper portion of said piling and rest- 70 ing on said bracket, and means for anchor- ing said concrete to said piling.

2. In a bulk-head construction of the character described, the combination with a wall of metallic sheet piling, of a plurality 75 of anchor brackets secured to the upper por- tion of the outer face thereof, a concrete fac- ing applied against the face of said piling and secured thereto by the brackets afore- said.

3. In a bulk-head construction of the character described, the combination with a wall of metallic sheet piling, of a substan- tially horizontal longitudinal support se- 80 cured intermediate of the ends thereof, a 85 concrete facing resting on said support, and means for anchoring said facing to the piling.

4. In a bulk-head construction of the character described, a wall of metallic sheet 90 piling provided with a channel support ex- tending longitudinally of an intermediate portion thereof, a concrete facing carried by said support and metal fabric reinforcing 95 embedded in said concrete.

5. In a bulk-head construction of the character described, a wall of corrugated metallic sheet piling provided with angular brackets extending from the outer surface thereof, a metal plate supported by said 100 brackets, provided with an outer upwardly projecting flange and a horizontal portion formed into scallops or corrugations adapt- 105 ed to fit within the corrugations of said pil- ing, thereby forming a base or support for facing material adapted to rest thereon.

6. In a bulk-head construction comprising a wall of metallic sheet piling, the lower end of which is driven into and embedded 110 into firm earth or similar material, anchors extending from the upper portion of said piling into solid material in the rear there- 115 of, a longitudinal support secured to the front surface of said piling at a point inter- mediate of the ends thereof, a concrete fac- 120 ing, the lower portion of which rests on said support, means for anchoring said facing to said piling, a timber string piece secured to the upper portion of the concrete facing and anchored to the piling aforesaid.

7. In a bulk-head construction comprising a wall of metallic sheet piling, the lower end of which is driven into and embedded into firm earth or similar material, anchors extending from the upper portion of said 125 piling into solid material in the rear thereof, a longitudinal support secured to the front surface of said piling at a point interme-

diate of the ends thereof, a concrete coping and facing, the lower portion of which facing rests on said support, means for anchoring said facing to said piling, a timber string piece secured to the upper portion of the concrete facing and anchored to the piling aforesaid.

In testimony whereof, I hereto affix my signature in the presence of two witnesses.

JULIUS R. WEMLINGER.
